UNITED STATES PATENT OFFICE.

AUGUSTUS H. JENSEN, OF CHENEY, WASHINGTON.

CONTAINER AND CUTTER FOR RUBBER-DAM SHEETS.

1,239,695.

Specification of Letters Patent. Patented Sept. 11, 1917.

Application filed October 20, 1916. Serial No. 126,758.

To all whom it may concern:

Be it known that I, AUGUSTUS H. JENSEN, a citizen of the United States, residing at Cheney, in the county of Spokane and State of Washington, have invented new and useful Improvements in Containers and Cutters for Rubber-Dam Sheets, of which the following is a specification.

- This invention relates to a container and cutter for rubber dam sheets such as commonly employed by dentists in preparing rubber dams for use in the mouth of a patient during dental operations, the object of the invention being to provide a container 10 wherein the rubber sheet may be inclosed and protected in a sanitary manner from dust, dirt, etc., and from which container the sheet may be drawn and portions severed therefrom for use as occasion requires.
- 15 A further object of the invention is to provide a container of a construction to admit of the withdrawal of the rubber sheet material with a proper degree of resistance, the projection of a smaller portion of the material therefrom that it may be easily gripped for drawing out fresh material as needed and the severance of the drawn out portion of the sheet in a ready and convenient manner.
- 20 The invention consists of the features of construction, combination and arrangement of parts hereinafter fully described and claimed, reference being had to the accompanying drawings in which:—
- 25 Figure 1 is a perspective view of a rubber dam sheet container and cutter embodying my invention.

Fig. 2 is a vertical transverse section through the same.

30 Fig. 3 is a detail section showing the construction of the hinge for the fixed cutter blade.

Fig. 4 is a view similar to Fig. 2 showing a slightly modified construction.

35 Referring now more particularly to Figs. 1 to 3, inclusive, of the drawing, wherein I have shown a container proper made wholly or largely of wood, 1 designates the container which comprises an oblong rectangular box or receptacle open at the top, except as hereinafter described. This receptacle is composed of a bottom 2 rear wall 3, end walls 4 and a front wall 5, which may be united in any suitable manner.

40 The front wall 5, when the receptacle is made of wood, is preferably made thicker

than the other walls, so that its upper surface will form a ledge or shelf 6 at the front of the top portion of the container, the remainder of said top portion of the container 60 being normally open and a lid or door 7 being provided for closing the same. This lid or door 7 is hinged or pivoted at its rear edge to the wall 3 by means of hinges 8, which are preferably of the spring type, 65 whereby through the force of gravity and the action of the spring hinges the door will be normally maintained in a closed position.

The sheet material 9 to be dispensed may be contained either loosely or in roll form 70 within the container and is adapted to be drawn outward between the inner edge of the ledge or shelf 6 and free edge of the door or lid 7. For the purpose of facilitating the sliding withdrawal of the sheet material between such edges of the ledge and door, the said edges are provided with lapping beveled surfaces 10 and 11, which, through the pressure of the door are designed to maintain a desired friction on the material to 75 prevent it from being too freely drawn outward, while at the same time permitting of its withdrawal without strain. These beveled overlapping abutment edges also serve to diminish the liability of the entrance of 80 dust and dirt, whereby the sheet of material will be inclosed and protected in a sanitary manner from contamination. The surface 10 is preferably comparatively broad so that the sheet material may have a comparatively 85 large bearing surface of a smooth character to rest against in the act of withdrawal, thus effectually preventing injury thereto.

The upper forward portion of the wall 5 is formed with a recess 12 receiving a fixed 90 cutter blade or plate 13, which lies flush with the outer surface of the wall 5 and with the upper surface of the ledge 6, and which is secured in position by screws or other suitable fastenings 14. This cutter blade or 95 plate is adapted for coöperation with a vertically movable cutter blade or plate 15 which is movable downwardly over the outer surface of the blade 18 to sever the drawn out portion 9' of the rubber dam sheet from 100 the top of the sheet, leaving just a small portion of the sheet projecting over upon the ledge 6 so that it may be easily and conveniently grasped when it is desired to withdraw a fresh portion of the sheet for severance.

The blade or plate 15 is provided at one

end with a hinge knuckle 16 connected by a pivoted pin 17 with a hinge member 18 fitted into the adjacent end of the wall 5, the blades 13 and 15 extending preferably 5 the full length of the container, so that a sheet of any width which can be accommodated within the container may be cut. At its free end the blade 15 is provided on its outer side with a finger piece 19 and on 10 its inner side with a stop member 20, which latter is adapted to engage and clamp the portion of the sheet lying on the ledge 6 on the downward movement of the cutter to its fullest degree and to limit such movement of the cutter.

It will thus be seen that normally a supply of rubber dam sheet material may be kept within the container and protected, and that when it is desired to use a portion 20 of the sheet a proper amount may be drawn out and severed from the sheet. Also it will be seen that while the door 7 will allow complete access to the interior of the container, such door will normally close the container 25 and clamp the sheet so that the projecting marginal portion of the sheet will be held against displacement. Also it will be seen that the beveled surfaces of the container and door will allow the sheet to be readily 30 and conveniently withdrawn without injury.

In Fig. 4 of the drawing I have shown a construction of container 1^a which is made of sheet metal, the walls 2^a, 3^a, 4^a and 5^a being formed and united in any desired 35 manner. With this construction the edge of the wall 5^a is projected inwardly in the form of a flange 6^a forming the ledge, while the door 7^a may be made of sheet metal or other suitable material. With this construction 40 also the front wall 5^a is offset inwardly to form the receiving recess for the cutter blade or plate 13 while the free edges of the flange 6^a and door 7^a are properly bent or coiled to provide the lapping friction and clamping surfaces 10^a and 11^a. The cutting mechanism with this construction is the same as that previously described.

I claim:—

1. A container for rubber dam sheets comprising a receptacle having a ledge over which the free edge of the sheet is to be

drawn, a closure for the receptacle having an edge portion arranged to engage the material resting on said ledge, and a cutting device for severing a portion of the material drawn outward over the ledge, said receptacle being recessed along its front wall and having a deeper recess at one end communicating with the recess first mentioned, a hinge member having an offset portion positioned within the recess, said cutting device also including an offset portion constituting a hinge knuckle, and means for connecting the hinge member for positioning the cutting device to sever the sheet along 65 a line coincident with one upper edge of the receptacle at a point spaced from the point at which the sheet emerges.

2. A container for rubber dam sheets comprising a receptacle open at the top including a front wall having a portion projecting inwardly at the open top to form a ledge over which a portion of the sheet may be withdrawn, said ledge being provided with a beveled surface at its inner edge, and a door closing the top of the casing and having its free edge provided with a beveled surface adapted to engage the portion of the material resting against the beveled surface of the ledge, means positioned to cut 80 the sheet along a line lying substantially in the plane of the top and the outer portion of the front wall.

3. A container for rubber dam sheets comprising a receptacle provided with an opening in its top, and having one of its walls formed with a ledge along one of the margins of said opening and provided with a recess adjacent to said ledge, a cover for closing the opening in the receptacle, said cover and ledge being provided with beveled lapping friction surfaces, a stationary cutter member fitted in said recess and having an edge portion lying flush with the ledge, and a movable cutter member mounted for 90 coöperation with said stationary cutter member and spaced from the beveled lapping friction surfaces leaving a portion of the sheet projecting above the top after the cut has been made.

In testimony whereof I affix my signature.

AUGUSTUS H. JENSEN.
